TOILET TISSUE HOLDER

Henry Bolger, Portland, Oreg.

Application April 18, 1955, Serial No. 501,866

2 Claims. (Cl. 242—55.2)

This invention relates to a paper dispensing holder, and more specifically, the invention pertains to toilet tissue holders.

One of the primary objects of this invention is to provide a toilet tissue holder wherein the roll of paper may be inserted or removed therefrom through the operation of a pull rod.

Another object of this invention is to provide a toilet tissue holder of the type referred to above with pull rod means for effecting separation of the paper holding spindles while placing or removing a paper roll therein.

A further object of this invention is to provide a toilet tissue holder which is inexpensive to manufacture, non-complex in construction and assembly, and which is durable in use.

Other and further objects and advantages of the present invention will become more evident from a consideration of the following specification when read in conjunction with the annexed drawing, in which:

Figure 1 is a front elevational view, including a fragmentary portion of a wall, of a toilet tissue holder constructed in accordance with the present invention.

Figure 2 is a top plan view, partly in section, of the holder illustrated in Figure 1, the view being taken on the line 2—2 of Figure 1, looking in the direction of the arrows.

Figure 3 is an enlarged end elevational view, partly in cross-section, taken on the line 3—3 of Figure 1, looking in the direction of the arrows.

Figure 4 is an enlarged detail cross-sectional view taken on the line 4—4 of Figure 2, looking in the direction of the arrows.

Referring now more specifically to the drawing, the toilet tissue holder is seen to comprise a substantially hollow rectangular container 10 having an ornamental flange 11 integrally formed therewith and extending away therefrom adjacent an open side of the container. The flange 11 is adapted to be secured to the wall 12 by means of screws 13, and the same also serves to support the container within the wall of a room, as illustrated in Figures 1 and 2.

Paper roll holding spindles 14 are integrally connected with the arms 15 which are mounted substantially parallel to the end wall 16 of the container 10 exteriorly thereof. As is seen in Figures 3 and 4, the upper ends of the arms 15 are bent at right angles at 17 to provide end portions which are adapted to rest on the top wall 18 of the container 10. Shoulder rivets or bolts 19 extend through slotted guideways 20 and are fixedly secured to the top wall 18, as is illustrated in Figures 2 and 4.

A walking beam or bell crank lever 21 is pivotally mounted on the top wall 18 by means of a pivot bolt or rivet 22. The upper ends 23 of the arms 15 are pivotally connected to this beam at 24. One end of an operating pull rod 25 is pivotally connected to the walking beam at 26, and the other end thereof extends through an opening 27 disposed in the flange 11, and this end of the rod terminates in a button 28.

2

One end of a helicoidal spring 29 is connected at 30 to the walking beam 21, and the opposite end thereof is connected to the pin or rivet 31 which is fixedly secured to the top wall 18. As is seen in the drawing, the arrangement is such that the spring 29 is adapted to hold the walking beam in the position shown in the drawing, the spring holding the arms 15 in the full line position.

The spindles 14 extend through openings 32 which extend transversely through the end wall 16, the spindles 14 being locked in spaced confronting relation. The spindles 14 are adapted to enter the opposed ends of the tube or core 33 of a conventional roll of toilet tissue 34 to releasably secure the latter within the container 10.

When it is desired to remove or replace a roll of paper in the container, or to remove the core 33 of an empty roll therefrom, the spindles 14 are withdrawn from the full line position and take the position indicated in broken lines in the drawing. The above referred to operation takes place when the pull button 28 is pulled outwardly away from the container 10. As the operating rod 25 is moved, the walking beam 21 pivots about the rivet 22 against the tension of the spring 29 coming to rest in the dotted line position indicated in Figure 2. The operation of the walking beam simultaneously moves the spindles 14 away from each other to assume the broken line positions thereof, designated in Figure 2. The separation of the spindles 14, of course, permits the roll of paper to be inserted or withdrawn from the container. In either event, release of the pull button 28 by the operator frees the walking beam 21 for movement towards its original full line position, the movement being effected through the force exerted on the beam through the spring 29. This action will cause the spindles 14 to move toward each other and to engage within opposite ends of a toilet tissue roll, tube or core, as illustrated in Figure 4 of the drawing.

Having described and illustrated one embodiment of this invention, it will be understood that the same is offered merely by way of example, and that the invention is to be limited only by the scope of the appended claims.

What is claimed is:

1. A toilet tissue holder comprising a substantially hollow rectangular member having an open side, a continuous peripheral flange integrally formed on said member and disposed adjacent said open side, said member having a pair of opposed spaced side walls each of which are provided with a transversely extending aperture, said apertures being aligned with one another, a spindle mounted in and extending through each of said apertures, 50 a walking beam, means connecting each of said spindles with opposite ends of said walking beam, means disposed intermediate said ends of said walking beam pivotally connecting said walking beam on said member, manually operable means connected with said walking beam to effect rotation thereof about said pivotal means, and resilient means connected with said walking beam constantly tending to urge said walking beam for rotation in one direction about its said pivotal means.

2. A toilet tissue holder comprising a substantially hollow rectangular member having an open side, an integrally formed peripheral flange extending exteriorly of said member adjacent said open side, said member having a pair of opposed side walls each of which are provided with a transversely extending aperture, said apertures being in registry with each other, a paper roll spindle disposed within each of said apertures and extending into said member, said spindles being in opposed confronting relationship, a pair of arms, each of said spindles being fixedly secured, respectively, to one end of one of said pair of arms, said arms being disposed adjacent to and parallel with respect to said side walls, the other ends of each of said arms being laterally bent and slotted for

sliding engagement against a third wall of said member, said third wall being disposed intermediate said oppositely disposed side walls, a pin fixedly secured to said third wall and extending through each of said slots, a three-ended walking beam pivotally mounted on said third wall, means connecting a pair of ends of said walking beam with said other ends of said arms, a manually operable pull rod having one of its ends fixedly secured to the third end of said walking beam, the other end of said pull rod extending outwardly through said open side of said member, and

a helicoidal spring having one of its ends fixedly secured to said third wall and the other end thereof anchored on said third end of said walking beam.
